UNITED STATES PATENT OFFICE.

HUGO ROSENBERG, OF ALLEGHENY CITY, PENNSYLVANIA.

UMBRELLA-FASTENER.

SPECIFICATION forming part of Letters Patent No. 357,852, dated February 15, 1887.

Application filed November 18, 1886. Serial No. 219,260. (No model.)

To all whom it may concern:

Be it known that I, HUGO ROSENBERG, of Allegheny City, in the county of Allegheny and State of Pennsylvania, have invented a new and useful Improvement in Umbrella-Fasteners; and I do hereby declare the following to be a full, clear, and exact description thereof.

It has been usual to provide umbrellas or parasols with a fastening device consisting of a cord or band, one end of which is attached to a button, which is sewed to the outside of the cloth cover or made integral with one of the ribs, while the other end has a ring, which, when the umbrella or parasol is folded and the band passed around it, is looped over the button. The disadvantage of such fastening is, that the band hangs from the outside of the umbrella and is unsightly when the umbrella is opened, and, besides this, the strain of the band upon the cloth to which it is attached is apt to wear and to tear it, and thus to spoil or damage the umbrella.

It is the object of my invention to obviate this disadvantage and to provide an improved fastener which, while permanently attached to the umbrella, is not attached to the cloth nor to the outside of the cover, and does not need any peculiar construction of the umbrella for its attachment.

My invention is illustrated in the accompanying drawings, in which—

Figure 1 is a plan view of the fastener detached from the umbrella. Fig. 2 is a view of an open umbrella provided with the fastener. Fig. 3 is a view of the umbrella when folded.

Like symbols of reference indicate like parts in each.

Fig. 1 is made on a much larger scale than Figs. 2 and 3.

As shown in Fig. 1, the fastener consists of four parts—a cord, 2, which is preferably made of two strands twisted together, a button, 3, at the end of the cord, a band, 4, extending from the button, and a ring, 5, at the end of the band. The button 3 is preferably a flat-sided stud-button, which is attached to the cord 2 by spreading the strands at the end of the latter and looping them around the button's shank, and the band 4 is also attached to the shank of the button, though, if desirable, the parts 2 and 4 may form a continuous band or

cord with the button attached to the middle. The ring 5 is sewed to the outer end of the band in any suitable manner. The fastener 55 is applied as follows: The strands of the cord 2 are spread at the end and are looped around one of the stretchers of the umbrella on the inside next to the follower, as shown in Fig. 2. When the umbrella is opened, the fastener 60 hangs down from the stretcher beside the stick, as shown in Fig. 2, and is therefore in a convenient place and not at all in the way of a person carrying the umbrella. To use the fastener the umbrella is closed and the 65 follower, together with the point of attachment of the cord 2, is brought near to the handle, and the fastener itself extends beyond the cloth beside the handle. The umbrella is then folded in the usual way, without regard 70 to the fastener, and the projecting part of the cord is carried back or reflexed outside the folded cloth to its full extent, and the button 3 is held by the finger against the folds. The band 4 is finally carried around the folded 75 umbrella, and the ring 5 is looped over the button. This completes the fastening and holds the umbrella neatly folded, and the band itself is not apt to be displaced. To open the umbrella the ring is taken off the button and 80 then the whole fastener immediately loosens itself from the cover, and when the umbrella is raised it hangs down, as shown in Fig. 2. I prefer to make the band 4 of elastic cloth and the cord 2 of silk, though other materials 85 may be used, and, as stated before, the parts 2 and 4 may constitute a single continuous cord. The button 3 is preferably made of metal, and may be made ornamental in appearance in any suitable way. It may be provided with the initials or name of the owner 90 of the umbrella.

A hook may be substituted as an equivalent construction for the button.

The device as a whole is neat and very serviceable and durable. Its chief merits are, that it can be easily applied to an umbrella, and when used it does not abrade or tear the cloth, because it is not in any way attached thereto, and when the umbrella is raised it is entirely 100 separated from the cloth and cannot rub it.

If desired, the fastener may be attached otherwise than as shown in the drawings, the only essential being that it shall be attached

to a part of the frame of the umbrella on the inside and not on the outside of the cover.

I claim—

1. The combination, with an umbrella, of a flexible fastening-band attached to the umbrella-frame inside the cover and not to the cover itself, said band projecting below the cover when the umbrella is closed, and being reflexed and encircling the umbrella, substantially as and for the purposes described.

2. As an umbrella-fastener, the combination of a flexible cord or band attached to the umbrella-frame on the inside of the cover, having a fastening device, 5, at the end thereof,

and a button arranged at an intermediate point, substantially as and for the purposes described.

3. The combination of the cord 2, looped to the umbrella-frame on the inside of the cover, a button, 3, a band, 4, and a fastening device, 5, substantially as and for the purposes described.

In testimony whereof I have hereunto set my hand this 16th day of November, A. D. 1886.

HUGO ROSENBERG.
